UNITED STATES PATENT OFFICE

EDWARD J. KEARNEY, OF WAUWATOSA, AND JOSEPH ARMITAGE, OF MILWAUKEE, WISCONSIN, ASSIGNORS TO KEARNEY-TRECKER CORPORATION, OF WEST ALLIS, WISCONSIN

RATE-CHANGING MECHANISM

Application filed December 31, 1923. Serial No. 633,648.

This invention relates to improvements in rate changing mechanism or change speed gearing and, more particularly, to a rate changer adapted for use upon machine tools and comprising a mechanism in which relative changes in speed are effected by the replacement or interchange of particular elements.

It is the primary object of this invention to provide novel and improved means for the operative connection of a driving with a driven element at widely variable rates of relative speeds. More particularly stated, it is our object to provide for the wide range of speeds aforesaid with relatively small increments of change.

It is a further extremely important object of this invention to provide a rate changer through which two operative driven elements may be interconnected for operation at various relative speeds with either of said elements at a relatively higher speed than the other.

As indicated above, it is contemplated that the rate changer hereinafter to be disclosed, will find a field of usefulness in connection with machine tools and particularly, with the driving trains leading to the work supporting table and to a work supporting spindle, such as may be mounted as an attachment upon such a table. Accordingly, it is a further object of this invention to provide a rate changer which, in conjunction with driving trains having certain characteristics hereinafter to be described, will be susceptible of adjustment for the actuation of the two driven elements aforesaid at relative rates providing for the leads necessary to the cutting of threads of all standard types.

It is purposed, further, to provide not only for the cutting of standard threads, but also for the cutting of threads which differ to various minute degrees from the threads ordinarily recognized as standard. In this manner, it is our purpose to provide for the cutting of threads in metals which are known to be subject to contraction or expansion during their subsequent treatment. It will be understood by those skilled in the art that

an operator provided with a rate changer

embodimenting this invention will be able, in cutting threads in a piece of metal which is later to be hardened or otherwise treated, to compensate in advance for the expansion or contraction which is expected to occur in the metal during such treatment.

Further objects of this invention are to provide an unusually concentrated mechanism for the purposes aforesaid, with few parts and of simple construction despite the extreme range of adjustment made possible through its use; to provide a rate changer embodying a plurality of sets of change speed gearing in compact form and in which such gearing will nevertheless be accessible when the changes in adjustment are necessary; to provide a rate changer in which relative speeds of the driving and driven elements are varied by taking off gears from their respective shafts and substituting others and in which an extremely wide range of adjustment with small increments of change is possible with the use of comparatively few individual gears; and in general, to improve, simplify and render more convenient rate changing mechanism of the general type to which we have referred to herein.

While this application is directed particularly to the rate changer per se, the disclosure will nevertheless include the application of a rate changer, embodying this invention, to a milling machine, in order that the advantageous functions which may be accomplished through the use of this invention may be clearly brought out. For this purpose, the rate changer is shown to be attached to a milling machine table in a manner adapted to establish variable relative rates of movement between a dividing head spindle and the table actuating member or screw. The machine will be discussed from the standpoint of milling machine practice and the means by which various spiral leads may be cut will be described.

In the following description it will be noted that brief reference will be made to the subject matter of various companion applications as follows:

to a dividing head, filed April 24, 1923, Serial No. 634,292.

The application of E. J. Kearney and Joseph Armitage relating to a machine tool drive, filed December 31, 1923, Serial No. 683,647, which matured into Patent Number 1,626,001.

The application of Joseph Armitage relating to machine tool drive, filed June 4, 1923, Serial No. 643,290, which matured into Patent Number 1,670,794.

In the accompanying drawings:

Figure 1 is a plan view of a rate changing device, embodying this invention applied to a machine tool table in a way to establish the drive claimed in application Serial No. 634,292, above referred to, for the actuation of said table and the work supporting or driving spindle of a spiral-cutting dividing head, such as forms the subject matter of application Serial No. 634,292, above referred to.

Figure 2 is a developed view in plan of the mechanism housed within the rate changing device shown in Figure 1 as connected with special driving mechanism housed within a machine tool saddle beneath the table and disclosed more particularly in the companion application of Joseph Armitage, Serial No. 643,290, above referred to.

Figure 3 is a section taken on line 3—3 of the developed view shown in Figure 2.

Figure 4 is a developed sectional view taken on line 4—4 of Figure 5, and illustrating the means by which the rate changing mechanism may be attached to a machine tool table.

Figure 5 is a fragmentary detail, partly in horizontal section, of a means for clamping the rate changing mechanism to the machine tool table.

Figure 6 is an end elevation of a housing in which rate changing mechanism embodying this invention may be assembled.

Figure 7 is a front elevation of the same.

Figure 8 is a section taken on line 8—8 of Figure 7.

Figure 9 is a detail of one set of change speed gearing incorporated in the rate changing mechanism as it appears in a section taken on line 9—9 of Figure 10.

Figure 10 is an end elevation of the mechanism shown in Figure 9.

Figure 11 is a section taken on line 11—11 of Figure 6.

Like parts are identified by the same reference characters throughout the several views.

A machine tool table shown at 10 may be reciprocable in the usual manner upon the machine tool saddle 11 within which is housed driving mechanism described in detail in the Armitage application, Serial No. 643,290. This driving mechanism will be very briefly described herein. The bevel pin-

ion, indicated at 12, is driven through a train, not shown, from some source of power extraneous to the machine. For the purpose of this description, the bevel pinion 12 may be considered to be itself a source of power.

Journaled for reciprocation with the table are two parallel shafts, one of which comprises a table actuating screw 13 and the other of which constitutes a power shaft 14. At one end of the table, each of these shafts will preferably be provided with clutch members shown at 15 and 16, respectively.

The axis of shaft 14 passes immediately above the bevel gear 12 and a pair of bevel gears 17 and 18 mounted concentrically with shaft 14 in constant mesh with gear 12 and are thereby interconnected for simultaneous rotation in opposite directions. Splined to shaft 14 are a pair of clutch members 20 and 21 which are connected for simultaneous axial movement upon said shaft. A handle 22 upon an oscillatory rock shaft 23 serves to transmit movement to the clutch members 20 and 21 through the teeth 24 upon the rock shaft and rack teeth 25 upon the clutch member 21.

The arrangement is such that when the handle 22 and rock shaft 23 are tilted in either direction from the neutral position in which they are illustrated, one or the other of the clutch members 20 or 21 will be engaged with the hub of gears 18 or 17, respectively, to receive motion from the gear so engaged and to actuate power shaft 14 in either direction accordingly. The clutch members 20 and 21, since they move in unison, may be considered as a single clutch device through which shaft 14 may alternatively be connected with either of the oppositely rotatable gears 17 and 18 to receive power therefrom.

Freely rotatable and concentric with respect to shaft 14 and axially movable on said shaft is a sliding clutch pinion 27 which is provided with a peripheral groove 28 within which a fork 29 is operatively engaged for the shifting of the pinion. The pinion is provided upon each of its ends with clutch teeth which, by the sliding movement of the pinion, are alternatively engageable respectively with complementary teeth upon the gears 17 and 18. The axial sliding movement of pinion 27, by means of which it may be coupled with either of the gears 17 or 18, is controlled by means of a rack bar 30 which carries the shifting fork 29. A handle 32 at the forward side of saddle 11 is oscillatory with a rock shaft 33 which carries a rack gear 34 meshing with a rack 35. From rack 35 reciprocatory motion is transmitted to rack 30 through the medium of a pair of connected rack gears 36 and 37.

Splined to the screw 13 is a gear 40 which is sufficiently broad so that despite any possible axial adjustment of clutch pinion 27, the pinion and said gear will always remain

in mesh. The splined connection of gear 40 with screw 13 is adapted to permit the screw to move axially through said gear with the table 10 while the gear maintains its position within the saddle. Screw 13 operates through a fixed nut 41 which is held to the saddle by any suitable means, such as dowel pin 42. Thus, by the suitable oscillation of handle 32 in either direction, the clutch teeth 5 of clutch pinion 27 may be brought into engagement with one of the oppositely rotatable gears 17 or 18, thereby causing said pinion, gear 40 and table screw 13 to rotate in a direction controlled by the direction of 10 rotation of the principal gear 17 or 18 engaged by pinion 27. Obviously, the rotation of the screw 13 in any given direction will produce a corresponding movement of table 10 through the feeding of the screw 13 15 through nut 41. Shaft 14 will move with the screw and table, being permitted by its splined connection with clutch elements 20 and 21 to have such movement.

A suitable interlocking device, designated 25 in its entirety by the reference character 43, is preferably used to prevent the simultaneous operation of the screw 13 and power shaft 14. This device has been fully described in the Armitage companion application, above 30 referred to, and need not further be discussed herein.

The whole purpose of the driving mechanism thus far described is to provide for the alternative actuation in 35 either direction of either the table screw 13 or the power shaft 14 from a single source of power, such as gear 12. It will be remembered that gears 17 and 18 are interconnected through gear 12 for continuous rotation in opposite directions. One 40 clutch device, comprising clutch sleeves 20 and 21, is operable to connect the power shaft 14 with either of the gears 17 or 18 and a second clutch device, comprising the clutch 45 pinion 27, is similarly operable to connect the screw 13 with either of the gears 17 or 18. Thus these two parallel shafts, both of which 50 translate with the table, may either of them be driven in either direction, although their simultaneous actuation is preferably rendered impossible in the practical use of the present invention.

Machine tool tables are adapted to receive 55 various attachments and may include work supporting or driving spindles permanently mounted thereon. For the purposes of this description it is desired to illustrate a work supporting or driving spindle to be given through the rate changing device hereinafter 60 to be described. By way of exemplifying various types of work supporting spindles which may be supported from a machine table, there is illustrated herein a table attachment embodying such a spindle. The attachment 65 illustrated has been more particularly

described in the companion application of E. J. Kearney, Serial No. 634,292, above referred to, and will not be described in detail herein. The attachment may be designated in its entirety by the reference character 45. It 70 comprises a work supporting spindle 46 journaled in a frame 47 which is adjustably supported above a base member 48 clamped to the table 10. Motion is received into the attachment through a shaft shown at 49 and is transmitted through the attachment by means not shown here in to indexing mechanism generally indicated at 44 and thence to the work supporting spindle 46. As is usual in the case of dividing head mechanisms of 75 various types it may be understood that the internal mechanism of the dividing head 45 is such as to connect the driving shaft 49 with the spindle 46 in the ratio of 40 to 1. As above stated, the special features of the 80 dividing head, as described in the companion application above referred to, are unnecessary to an understanding of this invention and accordingly are not illustrated. For the 85 purposes of this description the device 45 may be taken to represent any well known type of table attachment providing for a rotatable, or otherwise independently operable, work support.

Removably mounted upon table 10 is a 90 housing 50 within which the rate changing mechanism, forming the particular subject matter of this application, is assembled. The 95 end of table 10 may be provided with a dovetailed tongue 51 as shown in Figure 1. Extending upwardly from the lower portion of housing 50 to a shoulder 52 is a complimentary recess 53, one wall portion 54 of which may be laterally adjusted to exert a clamping pressure upon the portion 55 of tongue 51. The 100 means by which the lateral adjustment of member 54 may be accomplished may comprise a screw 56 in threaded engagement with housing 50 and including a tapered portion 57 operating in a correspondingly tapered 105 recess 58 in an arm 59 connected with member 54. The arrangement is such that when the screw 56 is turned downwardly it is advanced by means of its threads to a point where the tapered portion 57 of the screw exerts a 110 wedging action on arm 59 to draw the member 54 into binding engagement with the portion 55 of dovetailed tongue 51. As a result 115 the entire housing 50 will be firmly clamped in the position defined by its dovetailed engagement with the table and by the limiting shoulder 52 which prevents the downward movement of the housing beyond a predetermined point. It will be obvious that any other clamping device might be used to engage the rate changer with the table without 120 affecting the operation of the rate changer as such.

When the housing 50 is clamped in the 125 above defined position, shafts 63 and 64 there- 130

in will be aligned, respectively, with the table screw 13 and the table power shaft 14. Each of the shafts 63 and 64 is axially-slidable in its bearings and is provided exterior to housing 50 with a manually engageable extremity, which may be grasped to accomplish the axial shifting movement. The shafts 63 and 64 are provided at their ends adjacent the table with clutch members 65 and 66 which are, respectively, engageable with the complementary clutch members 15 and 16 carried by the table screw and table power shaft. The axial shifting movement above referred to, may be utilized to engage and disengage either of the shafts 63 or 64 with the aligned shafts of the table. Thus by the suitable engagement of these clutch members it is possible to receive power into housing 50 through either the table screw or power shaft, whichever of said last mentioned members is actuated from the source of power within saddle 11.

While the mechanism within housing 50 preferably includes at least three sets of reduction gearing, there is nevertheless a transmission train provided for the direct actuation of the attachment spindle 46 from the power shaft 14 without using any of the change speed gearing. A pinion 68 fast on shaft 64 drives a gear 69 which meshes with a central gear 70. Gear 70 constitutes a point of union for a plurality of power transmitting trains hereinafter to be described. From this gear are actuated two driven gears 71 and 72 which are preferably of substantially equal size and are preferably journaled within the upper portion of housing 50 independently of the shafts to which they transmit power. The driven shafts 73 and 74 are interchangeably insertable into housing 50 and are provided with keyways through which said shafts may receive power from corresponding keys carried by the gears. Either of shafts 73 or 74 may be utilized conveniently for attachment actuation and which of said shafts is used and which gear, the operative shaft may be engaged with will depend primarily upon the nature of the attachment to be driven. In the accompanying drawing, shaft 73 is illustrated as being directly connected with the driving shaft 49 of the attachment 45. The connection is conveniently effected through the use of a coupling sleeve or other device of well known nature which is designated by reference character 76. In the event that the attachment to be driven could not be mounted with its driving shaft in alignment with the axis of gear 71 shaft 74 might then be used to transmit power from said gear. Shaft 74 will be noted to include a universal joint which is represented at 77. In the event that the power receiving element of the table attachment was disposed adjacent the rear of the table, rather than at the front thereof,

either of shafts 74 or 73 would then be used to transmit power from gear 72 to the attachment. Furthermore, if the attachment included two members which required simultaneous actuation it would be possible to use shafts 73 and 74 simultaneously to accomplish the desired result.

In addition to the operative power transmitting connection above described as extending between shaft 64 and the two driven shafts 73 and 74 it is to be observed that means is also provided for transmitting power through the central gear 70 between shafts 63 and 64 of housing 50. In other words, it is possible through the mechanism contained in said housing to connect the table power shaft 14 and the screw 13. In the power train which is available for this purpose there are preferably three sets of reduction gearing, each of which set may include substitute gears, whereby the rate of motion transmission through each such set may be varied according to the ratios of the gears used. For the purposes of the present application this change speed gearing of the so-called "take-off" type is preferred over other forms of change speed mechanism, since it makes possible the production of an unusually large number of speed changes with an unusually small number of individual gears. Gear 68 has already been described as being in mesh with gear 69. Said gear 69 may be mounted upon a relatively fixed stud 80 and may be connected with a worm 81 through which the motion of said gear is imparted to an automatic trip device which will herein be designated in its entirety by reference character 82 but will not be specifically described. The trip device 82 was described in companion application Serial No. 683,647, above referred to, and an understanding thereof is unessential to an understanding of this invention. It may be pointed out, however, that the trip device operates to move rod 83 axially and, through the movement of a clutch fork 84 connected with said rod and acting upon shaft 64, to disengage clutch members 66 and 16, whereby to disconnect shaft 64 from power shaft 14.

From gear 69, motion is transmitted as above described to gear 70 which is preferably fast upon shaft 85. This last mentioned shaft is connected with a shaft 86 through a series of change speed gears which will hereinafter be designated as Series A.

Shaft 86 is journaled in a bearing sleeve 87 supported by the portion 50' of housing 50. Upon the exterior of the projecting bearing sleeve 87 is journaled an arm 88 which is provided at 89 and 90 with arcuate slots concentric with the axis of shaft 86. Set screws 91, in threaded engagement with the portion 50' of housing 50, may be tightened upon the portion of the arm adjacent such slots to maintain said arm in any posi-

tion of rotatable adjustment above the bearing sleeve 87 upon which it is journaled. As a result of this arrangement the projecting portion of arm 88 in which slot 95 is disposed may be set to maintain said slot 95 at a plurality of angles. Radially movable in slot 95 is a nut 96 which may conveniently be tubular and may be provided with a head 97 adapted to find a bearing on the inner marginal portions of arm 88 adjacent slot 95. Threaded to the tubular nut 96 is a bolt 98 upon which is a bushing for the support of sleeve 100. The bolt may be tightened against the bushing to support the sleeve in any desired position of radial adjustment upon the arm.

The sleeve or hub member 100 is rotatably mounted upon the bushing on bolt 98 and is flanged at its inner end and provided at its outer end with threads upon which a nut 101 may be screwed. A keyway preferably extends axially of this sleeve and serves to permit of the mounting thereon of gears 103 and 104 for unitary rotation therewith and with each other.

Upon a portion of shaft 86 which preferably corresponds in diameter to the sleeve 100 there is mounted a gear 105. This gear may conveniently be held in position by a nut 106 threaded upon the reduced end of shaft 86 and acting upon a thimble 107, whereby its clamping pressure is applied to the gear 105. A projecting portion of shaft 85 will also preferably be of the same diameter as sleeve 100. Upon this last mentioned shaft portion a gear 109 will be held by a nut 110. It will be obvious that the angularity of arm 88 and the lateral position of the stud which supports sleeve 100 may be so adjusted as to permit a gear disposed at 104 to mesh with gear 109. Inasmuch as gears 103 and 104 are both splined to the bearing sleeve 100 and therefore rotate as a unit, it will be obvious that means is provided for the interconnection of shafts 85 and 86. Furthermore, since the shafts 85 and 86 and the rotatable sleeve 100 are all of like size it will be obvious that the several gears 103, 104, 105 and 109 will be of like internal diameter and, if they are all provided with suitable keyways, may be substituted for each other upon the several shafts. As a result of this arrangement a variety of relative speeds between shafts 85 and 86 may obviously be provided for even without additional gears other than those already described.

As a matter of fact, however, it is preferred that the Series A gearing will include, altogether, ten different gears, each of which is adapted to be mounted upon any of the three shafts of the series. For reasons hereinafter to be brought out, it is preferred that these gears shall have, respectively, the following numbers of teeth, to wit,—22, 23, 24, 25, 26, 28, 30, 32, and 33. It is, of course,

immaterial whether the ratios between the gears which make up Series A in this example is maintained in other devices. For the particular device herein disclosed, however, and for use in conjunction with the particular gears hereinafter to be described, and for the particular service for which the rate changer is intended in this example the ratios of teeth above given are considered most desirable.

Shaft 86 is connected with shaft 115 through gears which will hereinafter be referred to as comprising Series B. In Figure 2 these gears are illustrated as comprising spiral gears 116 and 117 demountably secured to shafts 86 and 115, respectively. It will be obvious, however, that either of these gears may be used upon either of the shafts above mentioned and that other gears adapted to mesh on like centers may also be substituted for the gears shown herein. Since shafts 86 and 115 are in different planes and cross at right angles, it will be obvious that a worm may be used upon one of the shafts and a worm gear on the other. In Figure 8, there is illustrated a worm 118 upon shaft 115 and a worm gear 119 upon shaft 86. Obviously the worm and worm gear might be transposed, since the distance between the centers of these two shafts is constant. Furthermore, the arrangement is such that the shafts themselves, upon the removal of the gears whereby they are intermeshed, may be withdrawn from their respective bearings and substituted each for the other. After such a change has been made the worm and worm gear or the spiral gear may be mounted upon either shaft as before.

The Series B gears preferably include three pairs of gears as follows: Spiral gears of 8 or 16 teeth, respectively, having a ratio of 1 to 2; a worm of quadruple thread and a worm wheel having 32 teeth having a ratio of 1 to 8; and a worm of single thread and a worm wheel of 32 teeth having a ratio of 1 to 32.

When it is desired to remove shaft 86 or to effect changes in the Series A gears it is only necessary to rotate a latch member 120 and thereby to release a door 121 in housing 50. The housing is provided with a knuckle 122 and the housing is provided with complementary knuckles 123. A suitable pintle 124 extends vertically through said knuckles and permits the door to swing outwardly when the latch 120 is released, thereby the ends of shafts 86, 85, and 100, and the adjusting screws for arm 88, are exposed and all necessary changes can be made.

When, however, access is desired to the Series B gears which are disposed deep in the housing it is necessary to provide for a different mode of access.

In the forward side of housing 50 is provided an outwardly opening chamber 125 terminating in a shoulder at 126. Within

this chamber a spider or frame 127 is slidably receivable to support from housing 50 a bearing 128 for shaft 115. The frame also supports a bearing 129 for a shaft 130 hereinafter to be described. The opening through which frame 127 is inserted into the housing and is removed therefrom is normally closed by a closure plate 131 which may be held in position by a pair of manually operable latch members 132. The closure plate may conveniently be provided with a flange 133 adapted to fit within the margin of the chamber 125 into which the spider or frame 127 slides. This flange may abut the frame as shown in Figure 8, thereby securing the frame rigidly in position against the shoulder 126 of housing 50. The arrangement is such that when the cover plate 131 is removed the entire spider or frame 127 can be bodily withdrawn from chamber 125 bringing with it shafts 115 and 130. When the spider is thus withdrawn it will be obvious from an inspection of Figure 8 that access to the Series B gears is readily afforded through the remaining opening. In fact, one of said gears will necessarily be withdrawn with the spider and can be changed in the open. To remove gear 116 it is only necessary to reach through chamber 125 and unscrew the nut or other securing means which holds said gear in place, whereupon said gear may be withdrawn from its shaft and another gear may be substituted therefor or the shaft may be bodily withdrawn through the door 121 in the manner already described.

The shafts 115 and 130 which are thus mounted in the removable spider or frame 127 are interconnected by a third set of change gears which will hereinafter be designated as Series C. While it is possible to provide any desired number of gears for use at this point, it has been found necessary for the particular purposes desired and in the particular combination of other gears mentioned herein to use only four different gears in Series C. The gears 135 and 136 which are shown in Figure 2 in mesh between shafts 115 and 130 may have a 1 to 1 ratio.

In Figure 8, however, are illustrated substitute gears 137 and 138, and which are of the ratio of 1 to 4. The gear 137, as illustrated, is so small as to make its construction for removal from the shaft impractical. Consequently, gear 137 is made integral with shaft 115' which may be bodily substituted for shaft 115 or for shaft 86. For the purpose of substituting gear 138 for gear 136, the shaft 130 is provided not only with a keyway, best illustrated in Figure 8, but also with a threaded extremity adapted to receive a lock nut 139. It will be noted that inasmuch as the shaft 130 is journaled in bearing 129 of the frame or spider 127, this shaft, together with shaft 115 or 115', will be withdrawn

from the device with the spider. Consequently, in withdrawing the spider to effect a change in the gears of Series B, it is unnecessary to alter or adjust in any way the gears of Series C. The Series C gearing is bodily removable from the device with the spider for any desired purpose. 70

In order to permit of the bodily removal of shaft 130 from the housing, while preserving the possibility of an operative connection of said shaft with shaft 63 of the housing, there is provided in alignment with shaft 130 a short length of shaft 140 which is journaled in a bearing member 141 supported directly from the housing 50. Shafts 130 and 140 are provided with mutually complementary clutch members 142 and 143, respectively. These clutch members are so designed that when the spider or frame 127 is properly seated against the shoulder 126, clutch members 142 and 143 will be operative for power transmission between shafts 130 and 140. When the spider or frame 127 is withdrawn from the chamber 125 of the housing, clutch members 142 and 143 will be freely separable to permit of the manipulation of the device in the manner already described. 75 80 85 90 95

A motion reverser is preferably interposed between shafts 140 and 63. A bevel gear 145 carried by shaft 140 meshes with the opposed bevel pinions 146 and 147 which are mounted concentrically with shaft 63 but are free for movement thereon. Not only can shaft 63 be moved axially through pinions 146 and 147, but said pinions are also rotatable with respect to the shaft unless they are secured thereto through the medium of an axially slid able clutch member 150 which is splined to shaft 63 and serves to permit the engagement of either of the pinions 146 or 147 in operative power transmitting relation with said shaft. The movements of the clutch member 150 are controlled by a fork 151 mounted upon a slid able rod 152 extending to the exterior of housing 50, where it may be grasped for manual operation. 100 105 110 115 120

Through the provision of the motion reverser just described, it will be obvious that shafts 63 and 64 within housing 50 may not only be connected through a variety of change speed gearing but may also be connected for rotation in opposite directions. In other words, the construction illustrated is such that shaft 64 (and the two shafts 73 and 74 connected therewith) may be connected with the table screw 13 for rotation in any desired relative directions irrespective of whether the table screw 13 or the table power shaft 14 is primarily actuated. Furthermore, through the various clutches provided in this device (to-wit, clutch members 16 and 66; 15 or 65; or the clutch member 150) such parts of the mechanism as may be desired can be brought to rest while permitting other parts to remain active. 130

Note further that each set of change speed gearing above described includes potentially operative clutch mechanism since, upon the removal of one of the take-off gears, power transmission through the series of which that gear is a part must cease.

A complete power transmission train through housing 50 has now been described, and it will be remembered that this train includes no less than three different series of change speed gears which have been identified above as Series A, Series B, and Series C, respectively. In the Series A and Series B rate changing devices, all of the gears are interchangeable and may be substituted each for the other in their respective series. The Series C gears, while they may obviously be made interchangeable like the others, need not be so made to satisfy the requirements of the particular field of usefulness above described. That is, the gears of Series C need not be interchangeable within the series. It is preferred, however, that the gears of Series C and the gears of Series A shall be bodily interchangeable with the other. For this reason, shafts 85 and 86 are preferably made of equal diameters with shafts 115 and 130, and the distance between centers of the first pair of shafts is preferably identical with the distance between centers of the last mentioned pair of shafts. Thus, if the arm 88 and the several gears comprising Series A are removed from the position in which such gears are illustrated, it will be obvious that gears 135 and 136 may be substituted to connect shafts 85 and 86 operatively. Furthermore, the bearing member 129 of the spider or frame 127 is preferably provided with a hub portion 154 which is adapted to receive and rotatably support the arm 88. The web 155 whereby the bearing member 129 is supported in frame 127 may also conveniently be provided with apertures corresponding to those apertures in the housing portion 50' which receive the set screws 91 whereby the arm 88 is secured in any desired adjustment. Thus, the entire set of gearing comprising Series A may be utilized not only in the position in which it is illustrated in Figure 2, but also in substitution for the gearing above described as Series C.

The purpose for which the Series A and Series C gearing is thus made bodily interchangeable may be found in the fact that the Series B gearing is adapted to provide for a reversible mechanical advantage. In other words, when shafts 63 and 64 are interconnected through the train described above, either one may be made to rotate to a higher rate of speed than the other according as to whether the worm and worm gear comprising the Series B rate changer are disposed respectively on shafts 115 and 86 or on shafts 86 and 115. In the former

case the shaft 63 will obviously be the more rapidly moving element, whereas in the latter case shaft 64 will obviously be the more rapidly moving element. The same is true if the spiral gears are substituted for the worm and worm gear in Series B. In any event, the gears of Series B may be made to control the mechanical advantage between shafts 63 and 64 in such a manner that either of said shafts may have advantage over the other.

We have already described means whereby either of shafts 63 or 64 may be primarily actuated through the device housed beneath the machine tool table. In other words, if clutch pinion 27 is operative, the table screw 13 and shaft 63 may be driven in either direction. If the clutch device comprising sleeves 21 and 20 is operative, the screw will be stationary (except as driven through the train within the housing 50) and the power shaft 14 and shaft 64 in said housing will be primarily actuated in either direction. In this latter event the attachment actuating shafts 73 and 74 may also be said to be primarily actuated, since they will be driven directly from shaft 14 without the intermeditation of change speed gearing. Thus, there is provided within housing 50 a transmission train potentially operative to connect a table attachment with the table screw through a plurality of sets of change speed gearing and in such manner that either the attachment or the screw may be driven at a higher rate of speed than the other. It is, of course, preferred that the member which is operating at the higher rate of speed shall be primarily driven, particularly when the mechanical advantage between the driven members is high. Otherwise friction losses would be excessive, and if an attempt were made to drive from a worm gear to a worm the whole train might become frictionally locked.

The reason for making the Series A gearing bodily exchangeable with the Series C gearing will now be apparent. The Series A gearing, while desirable for the purpose of obtaining minute changes in mechanical advantage between interconnected shafts 73 and 63, is nevertheless inherently less sturdy and much lighter than any of the other gearing housed in the removable casing 50. Accordingly, it is preferred that the Series A gearing should always be located in the high speed end of the train within said housing so that the torque to be transmitted through said gearing will be relatively small and the strain thereon will be minimized. Thus, when the spindle 46 of the attachment is to be driven at speeds relatively greater than those of screw 13, the drive will preferably cut through clutch members 20 or 21 to the table power shaft 14, thence to the aligned shaft 64 within housing 50, thence to the cen-

tral gear 70 from which the attachment actuating shafts 73 and 74 are driven, thence through the Series A gearing which is thus located at the high speed end of the train, thence through the Series B gearing whereby the motion transmitted will be reduced in speed, thence through the Series C gearing and the motion reverser to shaft 63 and the aligned table screw 13. Such an arrangement is very desirable for milling threads of small pitch.

Where, however, the attachment is to be used for a spiral cutting operation in which threads of relatively long pitch are to be produced, it may be desirable to have the table screw 13 rotate at a rate much higher than that of spindle 46. In that event the clutch members 20 and 21 will be disposed in their neutral position as shown in Figures 1 and 2, and the clutch pinion 27 will be operated to transmit power with an initial speed reduction to gear 40 and to the table screw 13 which will thus be primarily actuated. Thence power is transmitted to shaft 63 with in housing 50 and through the motion reverser to the Series A gearing substituted for Series C gearing; thence to the Series B gearing which, in the present instance, will be arranged as shown in Figure 8 with a worm 30 on shaft 115 (or 115') and a worm gear on shaft 86. Thereby a reduction in rate will be effected at this point. Unless, however, the reduction is excessive, it will be obvious that the Series C gearing need not be substituted for the Series A gearing in the manner just described above. Assuming that the Series C gearing has been exchanged with the Series A gearing, motion will now be transmitted from shaft 86 to shaft 85 and central gear 70 through the Series C gears. From central gear 70 the shafts 73 and 74 are directly driven to actuate the attachment spindle 46 which thus becomes operatively connected at the slow speed end of a train of reduction gearing in which the table screw 13 is primarily actuated and is the high speed mechanism.

The structure and, in general, the mode of operation of the entire device has now been described and it is thus made possible for those skilled in the art to adapt this mechanism by the provision of suitable ratios of gears for any desired purpose. Hereinafter, however, the function of the particular ratios of gears above described will be elaborated upon in order to make clear the adaptability of this device for use in machine tool practice.

Since changes in mechanical advantage are primarily controlled in the Series B change speed gearing, or, in other words, since the greatest changes in mechanical advantage are effected at this point, it will probably be desirable to discuss first the effect of the various gears provided for use in the B Series.

Through the medium of the gears above described, other things being equal, the following ratios may be established between shafts 115 and 86: 1/32; 1/8; 1/2; 2/1; 8/1; and 32/1.

The gears of Series A may be arranged with 70 33 and 22 toothed gears acting as drivers, and with the 22 and 24 toothed gears acting as driven gears, in which case they will produce a combined ratio of $33/22 \times 32/24 = 2/1$. 75 Since this combination is also reversible, this maximum ratio may be used to give either of shafts 85 or 86 a mechanical advantage of 2/1 over the other. Thus, if the gears of A Series and the gears of the B Series 80 are combined to produce their maximum or extreme ratios, it will be obvious that the relative rates of motion between shafts 85 and 115 may be $1/32 \times 2$ or $32 \times 2/1$, respectively.

The C Series of gears may either serve to 85 transmit the above motion unchanged, providing the equally sized gears 135 and 136 are used, or they may lower the rate in the ratio of 4 to 1 for the transmission of power in one direction. These gears, in the present 90 embodiment of our invention, effect a reduction in the rate of motion transmission in one direction only, since they have been described as being non-reversible. Thus, if all the gears of the three series are used to produce their extreme effects, it will be obvious 95 that the relative rate of movement between shaft 85 and screw 13 may be as high as $32 \times 2 \times 4$ or may be as low as $\frac{1 \times 1}{32 \times 2}$. In 100

other words, shaft 85 may make 256 rotations to one rotation of screw 13 or may make 1/64 rotation to one rotation of the screw.

Between the two extremes above described, 105 a vast number of intermediate speeds may be obtained. It has already been pointed out that six different ratios may be established in the Series B gearing through the substitution or interchange of gears upon shafts 115 and 86. These speeds comprise a geometrical 110 series with a constant multiplier of four. These various speeds, when modified by the gears of C Series, still have a constant multiplier of four, since the possible effect of the C Series is merely to produce a change in the ratio of 1 to 4, and thereby to add one term to the geometrical series produced by the B Series of gears.

It is the gears of the A Series that the 120 greatest number of changes of rate may be effected. Without going into detail, it may simply be stated briefly that it is calculated that with only the above described gears of Series A 868 different ratios may be produced between the shafts connected by these gears. It will be obvious that these 868 possible changes will be available throughout each 125 step of the geometrical series established by the Series B and Series C gears. Further- 130

more, since the difference in the number of teeth of the gears of the A Series is comparatively very small, the difference between the several rates of the 868 possible combinations which they can produce will likewise be relatively small. The ratio of motion transmission between shaft 85 and the spindle or work supporting member 46 is constant and may thus, for the moment, be left out of consideration. Considering only the change speed gears in the rate changer above described, it is calculated that a total of some six thousand and seventy-six different relative speeds are obtainable between the table screw 13 and the work supporting spindle 46.

Assuming that the lead of the table screw is $\frac{1}{4}$ inch, and that the reduction obtained through the interior mechanism of the dividing head is 40 to 1, (in accordance with the usual practice) the range of relative speeds obtainable in the rate changer which forms the subject matter of this application will be such that the maximum comparative table speed will be in the ratio of 512 inches of table travel for each turn of the dividing head spindle and the minimum comparative table speed will be $\frac{1}{2}$ inch of table travel for each turn of the dividing head spindle. Between these extremes the relative rates of table travel and spindle rotation are such that any of the threads in ordinary use may readily be cut with exactness. The above statements assume that the combined effect of the non-adjustable portion of the train, including the screw, the mechanism within the dividing head and the combined ratio of the non-adjustable gears connecting the dividing head with shaft 85 represents a total basic lead of eight. This basic lead may be used to calculate any desired arrangement of gearing within the rate changer if the following formula is followed, to wit:—the required effect of the rate changer is equal to the required lead divided by the basic lead of eight.

Assume, for example, that it is desired to machine a screw having $1\frac{1}{2}$ threads per inch. This will require the establishment of a driving connection through the rate changer which, considering both the change speed gearing and the invariable gearing, will be productive of $1\frac{1}{2}$ turns of the spindle for each inch of table travel. In other words, the lead required will be $2/23$ of an inch of table travel for each turn of the work supporting spindle. Applying the above formula, it is discovered that the required effect of the rate changer will be $2/23$ divided by 8, or $1/23 \times 1/4$. To achieve this result the Series B rate changer may be utilized to produce a 32 to 1 ratio, and the Series C rate changer utilized to produce a 4 to 1 ratio, whereby the combined effect of these two series of gears will be 128 to 1. The remaining effect to be produced by the Series A gearing will then be $128/1 \times 1/23 \times 1/4 = 32/23$. To produce this

result it is only necessary to use a 32 and a 25 toothed gear as drivers, and a 25 and a 23 toothed gear as driven gears in the Series A mechanism. In this way the required lead is exactly established and a screw having exactly $1\frac{1}{2}$ threads per inch may be machined. Other required leads may be obtained in the same manner.

Supposing, however, it is desired to deviate very slightly from a standard thread. Assume, for example, that a $1\frac{1}{2}$ pitch screw is desired but that this screw is to be produced upon a tap which is expected to shrink $1/10$ of 1 per cent when it is hardened. In other words, for each inch in length of the tap a shrinkage after machining of $1/1000$ of an inch is expected. To compensate for this shrinkage it is desired to cut the thread with a change of $1/1000$ in the lead.

Such special work as the above can readily be accomplished with the mechanism herein disclosed by the addition of special gears to the Series A set. For example, the desired increase in lead in the above specified instance can be quite closely approximated if a 34 toothed gear be added to the set. It will be obvious that two 33 toothed gears used in place of the two 25 toothed gears of the previous illustration would serve to give equivalent results. In other words, a $2/23$ lead would be obtained. $2/23$ expressed in thousandths is .08696. If, however, a 34 toothed gear be substituted for one of the 33 toothed gears in the above arrangement the result will be the production of a lead which, instead of

$2/23$, will be $\frac{1089}{12512}$. Expressed in thousandths the latter fraction is .087036. The difference between the two decimal fractions expressed above represents an increase in the lead of .000080, whereas it is desired to increase the lead by the one thousandth part of the former decimal or .000086. In other words, the desired lead would be obtained within six millionths. By resorting to smaller pitches or to other gears, the approximation might be made even more accurate, but in practice this would ordinarily be unnecessary. If such smaller variations from the terms of the progression were desired, however, it will be understood that two gears differing more widely in tooth numbers from those of the regular set might be substituted to produce a more minute differential value which might be added to or subtracted from the terms of the progression according as the larger gear is used as a driving or driven gear in the set.

From the foregoing explanation of the structure of this device, and from the examples which have been given as a guide for its use by those skilled in the art, it will be apparent that a vast number of changes in relative speed may be obtained by means of a rate changer embodying this invention, and with relatively few different gears arranged

in a very compact and convenient relationship.

It will be obvious to those skilled in the art that the rate changer herein disclosed is adapted for purposes other than those of machine tool practice. Wherever two or more members are to be operatively connected through rate changing mechanism susceptible of wide variations in relative speed, inversion of mechanical advantage or adjustment to provide minute variations from standard ratios, the above described device will be particularly useful. Its compactness, the ease with which it may be handled, and the accessibility of its entire mechanism, all will recommend it. It appears, therefore, that the objects of this invention as hereinbefore specified are wholly satisfied by the mechanism disclosed.

20 We claim:

1. In a rate changer, the combination with a pair of shafts whose axes are relatively angular and in different planes, of a pair of reduction gears interchangeably mounted upon said shafts and adapted for operative mesh irrespective of which shaft supports any given gear, whereby said gears are adapted to change the relative rate of motion transmission between said shafts when interchanged.

2. In a rate changer, the combination with a pair of shafts, of rate change elements comprising a worm and worm wheel each adapted to be interchangeably mounted upon either of said shafts and adapted for mesh in either relative position.

3. In a rate changer, the combination with a pair of shafts, of a plurality of sets of gears interchangeably mountable upon said shafts in operative mesh, one of said sets comprising a worm and worm gear, and another of said sets comprising a pair of spiral gears.

4. In a rate changer, the combination of a pair of shafts whose axes are relatively angular and in different planes, and a first and second pair of gears each adapted to be mounted upon said shafts, the gears of each pair being interchangeable and adapted to vary the relative shaft rates when interchanged.

5. In a rate changer, the combination of a pair of shafts whose axes are relatively angular and in different planes, and a plurality of sets of change speed gears interchangeably mountable upon said shafts in operative mesh, each set being composed of reduction gears interchangeable within the set.

6. In a rate changer, the combination with a pair of shafts, of two pairs of rate change elements interchangeably mountable upon said shafts in operative mesh, said sets being adapted to establish differing rates of motion transmission between said shafts, and one of

said sets comprising a worm and worm wheel.

7. In a rate changer, the combination with a pair of shafts whose axes are relatively angular and in different planes, of two pairs of gears, each pair being adapted to be mounted in operative mesh upon said shafts and the gears of each pair being interchangeable within the pair, one of said pairs embodying spiral gearing.

8. In a rate changer, the combination of a pair of shafts and a plurality of pairs of gears, each pair being adapted to be mounted upon said shafts in operative mesh, and the gears of each pair being interchangeable within the pair, one of said pairs including a worm and worm gear and the other of said pairs including spiral gears.

9. In a rate changer, the combination with a pair of shafts whose axes are relatively angular and in different planes, a third shaft, variable means for effecting motion transmission between the shafts of said pair, and variable means for effecting motion transmission between one of the shafts of said pair and said third shaft.

10. In a rate changer, the combination with three shafts, two of said shafts being disposed with their axes relatively angular and in different planes, of a pair of gears mutually interchangeable and adapted to mesh between one pair of said shafts, and a second pair of gears mutually interchangeable and adapted to mesh between a second pair of said shafts.

11. In a rate changer, the combination with a first pair of shafts and a third shaft parallel to the axis of one shaft of said pair and adapted to comprise therewith a second pair, of a worm and worm wheel interchangeably mountable upon the shafts of the first pair in operative mesh, and reduction spur gears interchangeably mountable upon the shafts of the second pair in operative mesh.

12. In a rate changer, the combination with a pair of shafts disposed with their axes relatively angular and in different planes and a third shaft parallel to one shaft of the pair and adapted therewith to comprise a second pair, of transmission means to connect all three of said shafts and including for each pair of shafts a plurality of sets of gears of differing ratios alternatively available for motion transmission between the shafts of each pair.

13. In a rate changer, the combination with a first shaft, a second shaft, and a third shaft, two of which are disposed with their axes relatively angular and in different planes, of a plurality of interchangeable sets of reduction gears adapted to mesh between the first and second shafts, and a plurality of interchangeable sets of reduction gears adapted to mesh between the second and third shafts, the gears of a plurality of said sets being in-

- terchangeable within the set, whereby to make available a multiplicity of speed changes between the first and third shafts.
14. In a rate changer, the combination with a first shaft, of a second shaft parallel thereto, a third shaft arranged with its axis angularly disposed and in a different plane with respect to the axis of the second shaft, a fourth shaft parallel to the third shaft, variable speed gearing connecting said first and second shafts, variable speed gearing connecting said second and third shafts, and variable speed gearing connecting said third and fourth shafts.
15. In a rate changer, the combination with a pair of shafts arranged with their axes relatively angular and in different planes, of two other shafts respectively parallel to each of the first mentioned shafts, a set of reduction gearing connecting said first mentioned shafts, two sets of reduction gearing respectively connecting each of said other shafts with one of said first mentioned shafts, the gears of a plurality of said sets being mutually interchangeable within the set, whereby to vary the relative rates of speed between the shafts interconnected.
16. The combination with a series of four shafts arranged for operative gear transmission consecutively from one shaft to the other throughout said series, two of said shafts being disposed with their axes at an angle and in different planes, of a plurality of gear sets for each pair of shafts in said series, some of said gear sets being bodily interchangeable to establish operative power transmission between their several shafts, and the gears of a plurality of said sets being interchangeable within the set and comprising reduction gears, whereby to vary the rate of motion transmission between the shafts connected by said last mentioned sets.
17. In a rate changer, the combination with a pair of shafts whose axes are relatively angular and in different planes, of a plurality of gears interchangeable in pairs and interchangeable upon the respective shafts potentially available for the operative connection of said shafts, said pairs of gears comprising spur gear sets and a worm and worm gear set adapted to produce between the shafts a series of relative speeds in an approximate geometrical progression.
18. In a rate changer, the combination with a pair of shafts and means operatively adapted to actuate either shaft primarily, of a worm and worm wheel interchangeable mountable on said shafts, whereby power may be applied to the worm wheel through the worm irrespective of which shaft is primarily actuated.
19. In a rate changer, the combination with a pair of clutch controlled shafts each selectively primarily operable by power, of a worm and worm wheel interchangeably mounted on said shafts, whereby the worm may always drive the worm wheel irrespective of which shaft is primarily operated.
20. In a rate changer, the combination with a pair of shafts provided with motion transmitting connections whereby either may be primarily actuated by power, said shafts being disposed with their axes relatively angular and in different planes, of change speed mechanism potentially connecting said shafts and adapted for adjustment to provide for the operation of either shaft at a higher speed than the other.
21. In a rate changer, a power transmission train including change speed mechanism adjustable to provide for speed reduction from either end of said train to the other, and a set of gearing bodily transposable from a first position in said train to a second position in said train at the other side of said change speed mechanism, whereby a relatively high gear speed may be maintained in said gearing irrespective of the adjustment of said mechanism.
22. In a rate changer, the combination of a power train embodying transmission elements comprising means having relatively little strength, and a pair of transposable reduction gears productive of relatively high speed in either end of the train, said means being bodily transposable between positions in either end of the train, whereby to operate at relatively high speeds irrespective of the transposition of said reduction gears.
23. In a rate changer, the combination of a power train including at an intermediate point change speed gearing adapted to produce speed reductions from either end of said train to the other, and a relatively strong transmission device and a relatively less strong transmission device mutually interchangeable between positions in said train upon either side of said change speed mechanism.
24. In a rate changer, the combination of a power train embodying a pair of transposable reduction gears, a relatively strong set of transmission gearing, a relatively less strong set of transmission gearing, and means for supporting said sets of transmission gearing interchangeably in said train upon either side of said transposable reduction gears, whereby said less strong set of transmission gearing may be used in the high speed end of said train irrespective of the position of said transposable gears.
25. In a rate changer, the combination with a power train embodying a transposable worm and worm wheel, of transmission elements comprising a pair of spur gears adapted to be shifted bodily from a position in the train upon one side of said worm and worm wheel to a position in the train at the other side of said worm and worm wheel, whereby a relatively high spur gear speed may be main-

tained irrespective of the relative position of the worm and worm wheel.

26. In a rate changer, the combination of a power train, gearing adapted to be shifted bodily between two spaced points in said train, and means for varying the relative speeds of portions of said train adjacent said points.

27. In a rate changer, the combination with 10 a pair of shafts, of reduction gears interchangeably mounted upon said shafts for operative power transmission at a speed reduction in either direction, a third shaft, power transmitting connections including speed 15 change mechanism connecting said third shaft with one of said first mentioned shafts, a fourth shaft, power transmitting connections between said fourth shaft and the other of said first mentioned shafts, said last mentioned power transmitting connections including a detachable portion and said portion being interchangeable with said change speed mechanism.

28. In a rate changer embodying a power 25 train adapted to receive power from either end, the combination in said train with a transposable worm and worm wheel, of two sets of motion transmitting mechanism mutually transposable between points in said 30 train upon either side of said worm and worm wheel, one of said sets of motion transmitting mechanism including a plurality of reduction gears mutually interchangeable within the set.

35. 29. In a rate changer, the combination with two shafts crossing at right angles, of reduction gears interchangeably mounted upon said shafts in operative mesh, and two sets of motion transmitting gearing connected in 40 series with each of said shafts respectively, one of said sets of gearing including an adjustably supported rotor adapted to receive 45 removably two of said gears and to support such gears in operative motion transmitting relation to other gears of said set.

30. A rate changing device including a housing, a pair of spaced shafts crossing at an angle within said housing, a bearing for one of said shafts provided in said housing, 50 a third shaft supported from said housing, change speed gearing including take-off gears operatively connecting said third shaft with one of said first mentioned shafts, a door in said housing rendering said gearing 55 accessible, and a frame demountably carried from the housing and provided with a bearing for the other of said first mentioned shafts, whereby said other shaft is bodily removable in its bearing from said housing.

60. 31. A rate changing device including the combination with a housing providing a bearing, of a first shaft journaled in said bearing, a frame bodily removable from said housing and including a bearing, a second shaft disposed in said bearing spaced from said first

shaft and with its axis at right angles thereto, and a set of interchangeable gears adapted to be mounted alternatively upon said shafts in operative mesh, said gears being accessible upon the bodily removal of said frame and second shaft from said housing.

70 32. In a rate changing device, the combination with a housing, of a pair of shafts supported therefrom, a frame removably supported from said housing, a pair of shafts supported from said frame, separable motion transmitting connections between the shafts of the frame and the shafts of the housing, and motion transmitting connections between the shafts of the frame, said last mentioned shafts and connections being bodily removable with said frame from the housing.

75 33. A rate changing device including the combination with a housing and a pair of shafts supported therefrom, of a frame removably supported in the housing, a pair of shafts supported in said frame, separable motion transmitting connections between each of the shafts of the frame and one of the shafts of the housing respectively, and reduction gearing potentially connecting the shafts of the frame, one of said motion transmitting connections comprising change speed gearing adapted to be rendered accessible upon the bodily removal of said frame from the housing.

80 34. In a rate changing device, the combination with a housing, of a frame removable therefrom, reduction gearing supported from said frame and accessible exterior thereto, change speed gearing disposed interiorly of said frame within the housing, and motion transmitting connections operative to transmit power between said reduction gearing and said change speed gearing when said frame is properly positioned within the housing, said reduction gearing being bodily removable with said frame and said change speed gearing being accessible upon such removal.

85 35. In a rate changing device, the combination with a housing, of a frame member removably supported therefrom, a pair of shafts rotatably supported from said frame member and bodily removable therewith, gearing adapted to operatively connect said shafts exteriorly of said frame member, a pair of shafts within said housing having their axes angularly disposed, and motion transmitting connections adapted to connect each of the shafts in said housing respectively with one of the shafts supported from said frame member.

90 36. In a rate changing device, the combination with a housing, of a pair of substantially parallel shafts supported for rotation therein, a frame removably mounted in said housing, a pair of shafts in said frame substantially at right angles to the shafts of the housing, gearing connecting the shafts of the

- the frame, motion transmitting connections including reversing means between one of the shafts in the housing and one of the shafts in the frame, said connections being separable, and motion transmitting connections including a pair of gears adapted to mesh substantially at right angles and arranged to connect operatively the other shaft in the housing with the other shaft in the frame, said gears being separable upon the withdrawal of said frame and the shafts carried thereby. 70
37. In a rate changer, the combination with a plurality of shafts arranged to be interconnected by gears; of a first series of gears adapted for demountable association with certain of said shafts in sets and productive of a geometrical series of speed ratios between shafts so connected; a second series of gears adapted for demountable association in sets with certain of said shafts in a transmission train including said first series, the sets of said second series of gears being productive of a geometrical series of speed ratios having a relatively small multiplier and modifying the effect of the ratios produced by the sets of the first series, whereby speeds intermediate the terms of said first series may be produced; and substitute gearing adapted for use in connection with certain gear sets of said second series, said last mentioned gearing being productive in said sets of minute variations from the terms of the second series. 80
38. In a rate changer, the combination with a set of gears having teeth in numbers comprising terms in an arithmetical progression; of a driving shaft adapted to receive singly certain of said gears; a driven shaft adapted to receive singly certain of said gears; an adjustable intermediate shaft adapted to support in pairs for unitary rotation certain of said gears, groups of said gears being adapted to produce a series of ratios between the driving and driven shafts comprising terms in a geometrical progression; and substitute gears adapted to be incorporated in certain of said groups and productive of ratios varying by relatively minute quantities from the terms of said geometrical progression. 85
39. In a rate changer, the combination with a set of gears having teeth in numbers comprising terms in an arithmetical progression; of a driving shaft adapted to receive singly certain of said gears; a driven shaft adapted to receive singly certain of said gears; an adjustable intermediate shaft adapted to support in pairs for unitary rotation certain of said gears, whereby said gears may be mounted in groups of four including two pairs of driving and driven gears, and said groups being adapted to produce a series of ratios between the driving and driven shafts comprising terms in a geometrical progression; and a substitute gear adapted to be fitted to any of said shafts and to be incorporated in one of said pairs, said last mentioned gear having teeth in a number adapted to add or subtract minute differences in ratio to said terms according as said gear is substituted as a driving or driven gear in a group. 90
40. In a rate changer, the combination with a set of gears having teeth in numbers comprising terms in an arithmetical progression; of a driving shaft adapted to receive singly certain of said gears; a driven shaft adapted to receive singly certain of said gears; an adjustable intermediate shaft adapted to support in pairs for unitary rotation certain of said gears, whereby said gears may be mounted in groups of four including two pairs of driving and driven gears, and said groups being adapted to produce a series of ratios between the driving and driven shafts comprising terms in a geometrical progression; and two substitute gears of differing numbers of teeth and adapted to be mounted alternatively as driving and driven gears in one of said groups to produce a differential effect of minute value, whereby to add or subtract minute differences in ratio to said terms, according as the substitute gear having the greater number of teeth is used as a driving or a driven gear. 95
41. In a rate changer, the combination with shafts provided with means for their alternative actuation, of a set of gears interchangeably reversible upon said shafts, whereby to effect a possible reduction in rate to the driven shaft irrespective of which shaft is primarily actuated, said gears being in ratios of one to two, one to eight, and one to thirty-two, respectively, of a second change speed mechanism coupled with one of said shafts and including a plurality of sets of gears whose tooth numbers form the terms of an approximate arithmetical progression, the difference in terms of which is relatively small, and gears of one change speed mechanism being adapted to modify speeds produced by the other irrespective of the direction of drive therethrough, whereby to result in a series of rate changes having relatively wide range and relatively small increments. 100
42. In a rate changing device, the combination with a first rate changer having elements alternatively available and productive of rates forming a substantially geometrical progression; of a second rate changer connected in series with said first rate changer and including a set of gears having teeth in numbers comprising terms in an arithmetical progression, a driving shaft adapted to receive singly certain of said gears; a driven shaft adapted to receive singly certain of said gears; an adjustable intermediate shaft adapted to support in pairs for unitary rotation certain of said gears; groups of said gears being adapted to produce a series of ratios between the driving and driven shafts 115

comprising terms in a geometrical progression, and substitute gears adapted to be incorporated in certain of said groups and productive of ratios varying by relatively minute quantities from the terms of said geometrical progression.

43. In a rate changing device, the combination with a first rate changer having elements alternatively available and productive of rates forming a substantially geometrical progression; of a second rate changer connected in series with said first rate changer and including a set of gears having teeth in numbers comprising terms in an arithmetical progression, a driving shaft adapted to receive singly certain of said gears, a driven shaft adapted to receive singly certain of said gears, an adjustable intermediate shaft adapted to support in pairs for unitary rotation certain of said gears, whereby said gears may be mounted in groups of four including two pairs of driving and driven gears, and said groups being adapted to produce a series of ratios between the driving and driven shafts comprising terms in a geometrical progression, and a substitute gear adapted to be fitted to any of said shafts and to be incorporated in one of said pairs, said last mentioned gear having teeth in a number adapted to add or subtract minute differences in ratio to said terms according as said gear is substituted as a driving or driven gear in a group.

44. In a rate changing device, the combination with a first rate changer having elements alternatively available and productive of rates forming a substantially geometrical progression; of a second rate changer connected in series with said first rate changer and including a set of gears having teeth in numbers comprising terms in an arithmetical progression, a driving shaft adapted to receive singly certain of said gears, a driven shaft adapted to receive singly certain of said gears, an adjustable intermediate shaft adapted to support in pairs for unitary rotation certain of said gears, whereby said gears may be mounted in groups of four including two pairs of driving and driven gears, and said groups being adapted to produce a series of ratios between the driving and driven shafts comprising terms in a geometrical progression, and two substitute gears of differing numbers of teeth and adapted to be mounted alternatively as driving and driven gears in one of said groups to produce a differential effect of minute value, whereby to add or subtract minute differences in ratio to said terms, according as the substitute gear having the greater number of teeth is used as a driving or a driven gear.

45. In a rate changing device, the combination of a first rate changer having two separate rate changing gear sets each of which includes gears alternatively available for the

production of rates in a series forming a geometrical progression, the rates produced by the gears of one set having a relatively large multiplier and the rates produced by the gears of the other set having a relatively small multiplier, said sets being connected together in series, whereby the output thereof is subject to change of rate produced in both sets, together with a second rate changer in series with said output and comprising gears having teeth according to the terms of an arithmetical progression and alternatively engageable in sets productive of a relatively minute increment of variation from any change of rate produced by the combined geometrical progressions of said first rate changer.
